UNITED STATES PATENT OFFICE.

CHARLES A. UFFORD, OF BOSTON, MASSACHUSETTS.

COLLAPSIBLE SKIRT-FORM.

1,168,444.

Specification of Letters Patent. Patented Jan. 18, 1916.

Application filed June 12, 1913, Serial No. 773,238. Renewed February 5, 1915. Serial No. 6,373.

To all whom it may concern:

Be it known that I, CHARLES A. UFFORD, a citizen of the United States, and a resident of Boston, in the county of Suffolk and State of Massachusetts, have invented certain new and useful Improvements in Collapsible Skirt-Forms, of which the following is a specification.

This invention relates to a skeleton form adapted to be secured to the lower end of a bust form and to support a skirt depending from a bust form, the skirt form being composed of a series of bands determining the diameter of the form and a series of longitudinal flexible strips intersected and pivoted to the bands and determining the length of the form, the pivotal connection between the strips and the bands enabling the form to be collapsed lengthwise, either partially to vary its length, or wholly to reduce it to compact form for transportation.

My invention has for its chief object to provide means for supporting the form either in its full or partly extended adjustment, and preventing its accidental collapse from said adjustment.

The invention has for its object to enable the waist and hip portions of the form to remain at their maximum length when the lower portion of the form is partially collapsed to decrease the length of the form.

Another object is to provide means whereby the form may be adjustably flattened laterally, as, for instance, when it is desired to vary the distance from hip to hip, relatively to the distance or space from front to rear.

To these and other ends, the invention consists in the improvements which I will now proceed to describe and claim.

Of the accompanying drawings, Figure 1 represents a side elevation of a skirt form embodying my invention, fully extended. Fig. 2 represents a side elevation showing a form collapsed for shipment. Fig. 3 represents a top plan view of the form. Fig. 4 represents a side view showing the lower portion of the form partially collapsed to reduce its length, the upper, or waist, and

hip portions remaining at their maximum length. Fig. 5 is a detail perspective view of one end of one of the annular bands. Fig. 6 is a detail perspective view of adjacent ends of two strut members hereinafter described, when said strut members are folded up. Fig. 7 is a detail perspective view of a preferred connection at the point where the annular bands and vertical flexible strips cross each other. Fig. 8 represents a fragmentary view showing the end portions of one of the adjustable bands and the bolt and nut which adjustably confine the end portions of the strip. Fig. 9 represents an enlarged sectional detail herein- 65 after referred to. Fig. 10 represents a section on line 10—10 of Fig. 3, showing the part hereinafter termed the strut which prevents the collapsing of the form. Fig. 11 represents a section on line 11—11 of Fig. 10. Fig. 12 represents a fragmentary view showing a modified form of the strut. Fig. 13 represents a partial side elevation showing a modification. Fig. 14 represents a fragmentary view showing another modification. Fig. 15 represents a fragmentary view hereinafter referred to.

The same reference characters indicate the same parts in all the figures.

My improved skirt form is composed of a series of annular bands 12 which determine the diameter of the form, and a series of flexible strips 13 which intersect or extend across the bands 12, and are connected thereto by pivots 14, the said strips determining the length of the form and being adapted to swing relatively to the bands to either partially collapse the form as shown by Fig. 4, or wholly collapse the same as shown by Fig. 2. Said bands and strips are preferably made of resilient sheet metal. Each band is preferably composed of two metal strips, each forming one-half of the diameter of the band, the ends of said strips overlapping as indicated in Fig. 8, and being provided with longitudinal slots 15 through which extend headed bolts 16 provided with clamping wing nuts 17, whereby the overlapping ends may be firmly clamped together, the bands being adjustable in di- 100

ameter by means of the slots and bolts and firmly secured by the bolts in any adjustment of which they are capable. The upper band of the series constitutes the waist band, and to it are adjustably connected angular brackets having vertical members 19, and horizontal members 20, Fig. 9, whereby the form may be secured to a base 21 of a bust form. The members 19 are pivotally connected with the waist band by the bolts 16 and nuts 17, and the horizontal members 20 are provided with keyhole-shaped slots 22 which receive the heads of screws 23 inserted in and projecting slightly below the base 21 of the bust form. Provision is thus made for quickly securing the skirt form to the bust form, the connecting means being wholly within the waist band so that there are no securing devices on the exterior of either form liable to catch and tear fabrics.

A central standard or strut is provided which extends vertically through the center of the form from bottom to top and is adapted to prevent the accidental collapse of the form, said strut being engaged with the two end bands of the series and with one or more of the intermediate bands.

The preferred construction of the strut and of the means connecting the same with the bands is that shown by Figs. 3 and 10, the strut being composed of a plurality of sheet metal members 24 having longitudinal slots 25 in their overlapping end portions. The strut members 24 are adjustably connected with each other and with the upper and lower bands and with any desired number of the intermediate bands by sheet metal cross bars attached to and extending across said bands, in such manner as to remain attached to the form when collapsed. Each cross bar is composed of two sections 27, the overlapping ends of which have longitudinal slots 28 which receive headed bolts 29 provided with clamping wing nuts 30. The outer ends of the cross bar sections 27 are bent to form ears 31, Fig. 3, which are connected by pivots 32 with the bands 12. The slots 25 and bolts 29 enable the length of the strut to be varied. When the strut members are clamped to the cross bar sections 27, the entire structure becomes self-supported and free from liability of accidental collapse.

In case it is desirable to partly collapse the form to reduce its length, leaving it in operative condition, the length of the strut is correspondingly adjustable by means of the slots 25. One end of each strut member is provided with an open slot 33, Fig. 2, adapted to swing into and out of engagement with the corresponding bolt 29, so that when the strut is to be rendered inoperative, the nuts 30 are loosened and the strut members are swung out of engagement with the

bolts 29 as indicated by Fig. 2, the other ends of said strut members remaining attached to the upper and lower cross bars 27.

Fig. 12 shows a modified form of the strut which is composed of two members 24^a which may be cylindrical wooden rods, and a tubular member 24^b attached to one of the members and telescopically engaged with the other, the members 24^a being provided with sheet metal sockets 35 having ears 34 adapted to be secured by the bolts 29 to the cross bars of the bands 12. When the strut is not required for use, its members are removed from the sockets 35.

Owing to the pivotal connection between the strips 13 and the bands 12, the form is liable to be racked, or distorted more or less while fully erected, because the strips are free to twist or turn on the pivots 14 from their vertical positions toward the inclined positions shown by Fig. 4, notwithstanding the fact that the form is supported by the internal strut. In other words, the strut does not entirely prevent a twisting movement of the strips 13, and the racking of the form. To render the connection of the strips to the bands practically rigid or non-pivotal and prevent the racking of the form by even slight twisting movements of the strips, I provide inclined sheet metal braces 36, these braces being pivotally connected to a portion of the structure, such as one of the bands 12, and separably engaged with an adjacent portion, such as the adjacent band, the inclination of the braces enabling them to prevent pivotal movements of the strips on the bands and hold the strips and bands in rigid relation to each other. One or any greater number of the braces 36 may be employed.

To enable the lower portion of the form to be partially collapsed, or shortened, as indicated by Fig. 4, without shortening the upper or waist and hip portion of the form, I make the longitudinal strips 13 in sections, each longitudinal strip including a lower section which extends continuously from the lower end of the form to the band designated 12^x, said band being at the lower end of the hip portion of the form, the upper portions 13^x of the strips being made in separate pieces, so that they may remain vertical while the lower portions are inclined. This structure also, of course, permits the upper section to be reduced in height, independently of the lower section. For instance the upper portion can be collapsed as indicated in Fig. 2, while the lower portion remains in the extended condition shown in Fig. 4.

The several headed bolts and their wing clamping ends may all be of the same size so that only one style of bolt will be required throughout the entire structure.

The lower ends of the upper sections 13^x of the vertical strips are preferably connected somewhat loosely to the upper ends of the lower sections of the strips and to the band 12^x to permit a limited vertical play of the waist and hip portions of the form. To this end the said upper sections 13^x are provided with elongated slots 38, Fig. 15, permitting the sections 13^x to have a limited independent vertical movement. These elongated slots 38 enable the sections 13^x to be made of uniform length, and still permit them to be adjusted to make the upper end of the skeleton form with a proper taper, it being understood, of course, that, owing to the shape of the hips, some of the sections 13^x will be inclined more or less away from the vertical. The slots 38 permit strips of uniform length to be used, and yet insure that the upper or waist-band will be horizontal.

The members 24 may be made of sections having ears 39, (Figs. 6 and 14), said struts and ears being slotted as at 41 (Fig. 6), each slot being continuous and extending both ways from the angle or bend. A bolt and wing-nut 40 is employed at each joint so made, so that when the strut members are fitted together, as shown in Fig. 14, with the ears 39 together, said bolt and wing-nut can be employed to make the said structure rigid. At the same time, this structure permits the sections or members of the strut to turn a little independently, considering the connecting bolts as pivots, so as to prevent twisting of the strut when the lower portion of the form is constructed, as shown in Fig. 4. By loosening the bolt and wing-nuts sufficiently, however, the bolts can be slid along to the other ends of the slots 41 and the sections or members of the strut can be folded up, as indicated in Fig. 6. Each of the upper strip sections 13^x may be composed of a plurality of sections pivoted together, as shown in Fig. 13.

To prevent the outermost overlapped end of the band 12 from projecting outwardly so that goods will be caught thereupon, I preferably form the extreme outermost end with ears 42 (Figs. 5 and 8), said ears being bent to form lips which embrace a slot upon the portion of the annular band 12 which is overlapped, as described. In order that these ears or lips may pass by a joint between a band 12 and strip 13, means are preferably provided for insuring that there shall be a space between the members 12 and 13, as best shown in Fig. 7, a suitable washer 43 being applied to the pivot rivet 14, between members 12 and 13.

The entire device may be mounted upon casters 44, as indicated in Fig. 4, said casters being attached to the lowermost annular band 12.

In practice, the upper end of the strut, 65 whether of the form shown in Fig. 10, or that shown in Fig. 12, will be suitably connected to the bust form to hold it relatively to the skirt form.

Referring to Fig. 3, it will be readily understood that since the cross-bar sections 27 are relatively adjustable, the length of the transverse connection as a whole, can be varied so as to flatten the hip portion of the skirt form, more or less, to increase or diminish the width of the hips, or increase or diminish the measurement from front to rear. This adjustment of the cross-bar sections 27, in connection with the adjustment of the bands 12, so as to vary the size, I regard as of importance, since these two adjustments combine to enable me to get accurately shaped hip portions of the skeleton form.

The strut construction provides for holding the top and bottom members of the form at a fixed distance apart, thereby enabling me to dispense with the usual base and supporting stand rising therefrom.

If it should be desired to employ only the lower part of the form shown in Figs. 1 and 4, that is, if the upper or hip portion of the skirt form were to be removed or dispensed with, and a longer bust form employed, the base of the bust form indicated at 21 in Fig. 9, would then, of course, be secured to the upper annular band of the lower portion of the skirt form. The bracket members 19 and 20, shown in Fig. 9, would have their vertical members 19 secured to the inside of the upper band of the skirt form in the same manner as illustrated in Fig. 9. It is essential, of course, that the brackets shall be inside of the upper ring, or annular member, because if they were to expand outside of the same, they would interfere with the folding of the skirt form.

Skirt forms composed of annular bands and vertical strips intersecting the bands and riveted thereto have been known for at least forty years, the rivets forming a pivotal connection between the bands and strips and permitting the swinging of the strips on the bands until the strips become helical and the form is vertically or longitudinally collapsed. Prior to my invention however no one has provided adequate means for firmly connecting the bands and strips to maintain the form rigidly erected, and releasable or adapted to be rendered inoperative to permit the collapse of the form. I have provided two forms of releasable means for this purpose, viz., first the bolts 29 and nuts 30, the nuts when set up preventing relative turning movements of the bands 12 and strips 24, and permitting such movements when loosened, and secondly the brace 36 pivoted to a portion of the structure and

4
 detachably secured to an adjacent portion, said brace being inclined relatively to the bands and strips and preventing relative turning movements thereof when secured at both ends to the structure, and permitting such movements when detached at one end therefrom.

I claim:—

1. A collapsible skirt form comprising a series of annular bands, the band at one end of the series constituting a waist band, a plurality of flexible strips each intersecting and pivoted to all the bands, so that the form may be longitudinally collapsed, a longitudinal internal strut adapted to prevent the collapse of the form, the strut being composed of detachably connected sections adapted to be separated to render the strut inoperative, and means for holding said sections connected to the form when the latter is collapsed.

2. A collapsible skirt form comprising a series of annular bands, the band at one end of the series constituting a waist band, a plurality of flexible strips each intersecting and pivoted to all the bands, so that the form may be longitudinally collapsed, and a longitudinal internal strut adapted to prevent the collapse of the form, the strut being composed of longitudinally slotted sections, and provided with devices engaging said slots whereby the sections may be detachably connected, and adjusted relatively to each other to vary the length of the strut.

3. A collapsible form comprising a series of annular bands, the band at one end of the series constituting a waist band, a plurality of flexible longitudinal strips each intersecting and pivoted to all of the bands, the waist band and the lowest band being provided with cross bars, and a longitudinal internal strut engaged with said cross bars to prevent the collapse of the form.

4. A collapsible form comprising a series of annular bands, the band at one end of the series constituting a waist band, a plurality of flexible longitudinal strips each intersecting and pivoted to all of the bands, the waist band, the lowest band and one or more of the intermediate bands being provided with cross bars, and a strut adapted to prevent collapse of the form and composed of separable sections separably connected with said cross bars.

5. A collapsible skirt form comprising a series of annular bands including a waist band, and a plurality of flexible strips, each intersecting and pivoted to all the bands, the waist band being adjustable in diameter and provided with means for securing it at different diameters, and with a longitudinally adjustable strut-engaging cross bar extending across the interior of the waist

band and composed of overlapping sections 65 attached to the waist band and provided with means whereby they may be secured together at different adjustments.

6. A collapsible skirt form comprising a series of annular bands including a waist 70 band and one or more hip bands below the waist band, and a series of flexible strips each intersecting and pivoted to all the bands whereby the form may be longitudinally collapsed wholly or in part, the said 75 strips being composed of elongated lower sections pivoted to the bands below the hip portion of the form, and shorter upper sections pivoted to the upper ends of the lower sections and to the waist and hip bands, 80 whereby the lower portion of the form may be partially collapsed without collapsing the upper portion.

7. A collapsible skirt form comprising a series of annular bands, a series of flexible 85 strips each intersecting all the bands, pivots connecting the strips and bands, the whole forming a structure which is longitudinally collapsible by pivotal movements of the strips on the bands, and a brace pivoted at 90 one end to a portion of the structure and adapted to be detachably connected at its opposite end to an adjacent portion of the structure, said brace being arranged when connected, to prevent pivotal movements of 95 the strips relatively to the bands.

8. A collapsible skirt form comprising a series of diametrically adjustable annular bands each composed of a flexible strip, the end portions of which overlap and are provided with longitudinal slots, and bolts engaged with said slots and provided with clamping nuts, whereby the bands may be maintained at any diameter to which they may be adjusted, cross bar sections secured 100 to and projecting inwardly from two or more of the bands and provided with slots at their meeting ends, bolts engaged with said slots and provided with clamping nuts whereby the cross bar sections are adjustably connected, a series of flexible strips each intersecting and pivoted to all the bands, and a longitudinally adjustable strut composed of slotted sections secured to the cross bars by the said cross bar bolts and 110 their nuts.

9. A collapsible skirt form comprising upper and lower portions, each of said portions being collapsible independently of the other, whereby the lower part may be collapsed, while the upper or hip part remains more or less expanded.

10. A skeleton skirt form comprising upper and lower sections, each of said sections consisting of a plurality of annular bands 125 and strips connecting said bands, the strips which connect the bands of the upper section having slot and pin connections with

the lower section, to facilitate adjustment of the taper of the upper section.

11. A skeleton skirt form comprising a series of annular bands and connecting vertical strips, said bands and strips pivotally connected and spaced somewhat from each other at the pivotal points of connection, the annular bands being divided, slotted and overlapped, the outer overlapped end having

ears embracing the edges of the upper portion of the band.

In testimony whereof I have affixed my signature, in presence of two witnesses.
